UNITED STATES PATENT OFFICE.

JOHN A. LEFFERTS, OF ELIZABETH, NEW JERSEY.

BATH-TUB.

No. 823,794.

Specification of Letters Patent.

Patented June 19, 1906.

Application filed April 22, 1905. Serial No. 256,912.

To all whom it may concern:

Be it known that I, JOHN A. LEFFERTS, a citizen of the United States, and a resident of Elizabeth, in the county of Union and State of New Jersey, have invented a new and Improved Bath-Tub, of which the following is a full, clear, and exact description.

My invention relates to a novel construction of bath-tubs, and the principal purpose thereof is to provide means whereby they can be enameled in different colors upon their outside and inside surfaces. As at present constructed it is necessary, if they are to be enameled all over by the dry process, to give bath-tubs the same color both upon the outside and inside. This is due to certain peculiarities involved in the sieving operation, into which it is not necessary to inquire at the present time. In order to provide for giving tubs two colors, both of them being applied by the ordinary process of enameling, I construct the tub in two parts and enamel them separately by the dry process.

Reference is to be had to the accompanying drawings, forming a part of this specification, in which similar characters of reference indicate corresponding parts in all the figures.

Figure 1 is a perspective view of a bath-tub constructed in accordance with the principle of my invention and partly broken away to show construction. Fig. 2 is a longitudinal sectional view thereof, and Fig. 3 is a perspective view of one end of the inner shell in inverted position.

The tub proper comprises a cast-iron shell *a*, having a flange *b* and giving the same appearance as a tub constructed in the ordinary way. This shell rests in a second cast-iron shell *c*, which is of a somewhat similar shape and is provided with a flange *d*, on which the flange *b* is designed to rest and which is concealed by the latter. The flange *b* is provided with lugs *b'*, having perforations for the reception of screws to secure the two flanges together. The lugs *b'* on the flange *b* also permit the flanges to be evenly fitted one upon the other in event of their becoming warped or twisted when heated.

The inner shell is the main part of the tub and is provided with the water-tight connections for pipes *e* and the like in the usual manner, while the outer tub is provided with perforations *f*. The outer shell is provided with lugs or feet *g* for supporting the tub. It will be seen that the outer shell constitutes a support which extends upwardly and permits the main shell *a* to be hung from its upper edges and freely suspended between them. 55

In the operation of enameling the inner shell is enameled in one operation and given any desired color, preferably a light one, while the outer shell is separately enameled with another color, preferably a dark one, 65 and then the two shells are assembled to form the complete tub. This does away with the necessity of painting the outside of the tub, which is usually done in order to avoid giving the tub an entire coating of 70 white enamel. It provides an inexpensive and convenient way of improving the appearance of bath-tubs and is believed to be the only practical way in which the same result can be accomplished by the dry or sieving 75 process of enameling.

Having thus described my invention, I claim as new and desire to secure by Letters Patent—

1. A bath-tub composed of two cast-metal 80 shells, each enameled by the dry process and one mounted within the other.

2. A bath-tub comprising a cast-metal outer shell, and a cast-metal inner shell 85 removably supported in the outer shell, each shell being enameled by the dry process, the outer shell being enameled on its outer surface in one color and the inner shell on the inner surface in a contrasting color.

3. A bath-tub comprising a cast-metal 90 outer shell having an outwardly-extending marginal flange, and a cast-metal inner shell closely fitting the outer shell and having an outwardly-extending marginal flange fitting upon the flange of said outer shell, each shell 95 being enameled by the dry process, the outer one on its outer surface and the inner one on its inner surface.

4. A bath-tub comprising an outer shell having a straight marginal and apertured 100

flange, an inner shell fitting within the outer shell and having a curved marginal flange provided with apertured lugs resting upon the flange of the outer shell, and screws passing through the apertures of the flange of the outer shell into the apertures of said lugs.

5 In testimony whereof I have signed my

name to this specification in the presence of two subscribing witnesses.

JOHN A. LEFFERTS.
